[57] ABSTRACT

A processing apparatus for the development and associated manipulation of image record media (cassettes) having latent electrostatic images formed on an insulative film removably attached to the medium. The apparatus embodiment comprises a plurality of successive stations including an initial "entry station" where the "record" (i.e. an imaging plate including the image film and associated rigid support means) is automatically separated from the rest of the cassette; an automatic "toning station" with associated record positioning means adapted to bring the record into operative relation with toner delivery means and to automatically deliver an appropriate portion of toner uniformly to the film surface; a "fixing station" whereat the image, so toned and developed, is fixed upon the record film; and transport means for automatically advancing the record from one station to the next in a prescribed controlled, repeatable manner. The particular embodiments shown are especially adapted for handling ionographic cassettes of the "prepackaged" type.

IONOGRAPHIC FILM PROCESSOR AND ASSOCIATED METHOD

This is a continuation, of application Ser. No. 300,311, filed Oct. 24, 1972.

BACKGROUND OF THE INVENTION

This invention relates to apparatus and related methods for automatically manipulating unit record media, advancing them through a series of stations; and particularly to applications of such apparatus for the handling of image records bearing latent electrostatic charge images.

More specifically, this invention relates to improved cassette-handling mechanisms for advancing cassette units seriatim past various automatic treatment stations such as those adapted for unwrapping and (at least partially) disassembling the cassette to extract the "image record," for applying toner particles and then projecting fixing radiation to this record and for ejecting the treated record for further use; while storing the other, (non-image) portions of the cassette. Such mechanisms are described and illustrated as especially adapted for "Ionogram Cassettes."

BACKGROUND ART

The phenomenon known as Ionography and its underlying principles have been known for some time and involve the generation and development of X-ray images utilizing photoemissive source means and electrostatic image media, as opposed to silver halide film media commonly used at present for X-ray imaging. Xeroradiography is similar, but involves photoconductive, rather than photoemissive, imaging means. A primitive version of the basic ionographic process was disclosed by Chester Carlson in U.S. Pat. No. 2,221,776; later, by E. L. Criscuolo in NAVORD Report 4033, dated July 6, 1955, and in related U.S. Pat. No. 2,900,515 issued Aug. 18, 1959. An article by R. A. Youshaw and J. A. Holloway in Non-Destructive Testing, Volume 17, September-October 1959, page 297, and another by K. H. Reiss in Z. Angew Physik, 1965, Volume 19, page 1, gave further initial details.

The Basic Process

The ionographic process, basically, employs two parallel planar electrodes, defining an intermediate "working gap" across which a DC potential is established so that, with a given (positive) potential on the anode and a relatively negative potential on an operatively-adjacent cathode, an ionographic imaging unit is provided to receive an X-radiation image pattern and record it, electrostatically. This "working gap" should be arranged to receive all the X-ray energy possible for optimum results; accordingly, any intervening electrode or other structure is made as radiotransparent as possible (to the X-ray photon flux). Thus, where such an ionographic anode is disposed between the X-ray source and the working gap it is made relatively radio-transparent and has affixed to it an image-receiving dielectric "receptor" sheet. This sheet faces the "working gap" and is adapted to receive and retain electrostatic charge patterns corresponding to the incident X-radiation pattern. The receptor sheet may comprise a thin plastic film (e.g. Mylar by du Pont) or the like and will exhibit good charge-retaining, dielectric, properties.

The cathode, on the other hand, is adapted to support a photoemitter layer confronting this receptor

sheet across the working gap, and is adapted to generate charged particles (electrons, ions) in direct proportion to the amount (and kind) of incident X-radiation, and in this manner, project onto the receptor sheet an electrostatic charge-image corresponding to the pattern of incident radiation. This photoemitter may comprise a thin film of lead, lead oxide, or other efficient absorber of X-radiation (see the aforementioned Reiss reference where lead and like heavy metals are designated). The receptor sheet and photoemitter are thus separated by a prescribed fixed distance defining this "working gap," with the X-ray subject being disposed outside, preferably on the anode side. A quenching gas may be provided in the gap; in some instances being flowed therethrough.

As workers in the art well know, when a subject is disposed adjacent this anode and the radiation (usually X-ray photons; although gamma ray photons may, at times, be feasible), is projected into the subject, being differentially absorbed thereby, the amount of flux passing through the subject, and not absorbed, is inversely related to the amount and kind of mass through which it must pass. The emergent radiation pattern, thus representing a sort of "shadow image" of the subject's cross-sectional mass, is then passed through the relatively transparent anode and associated receptor sheet to cross the working gap and strike the photoemitter surface where it is intended to be substantially absorbed. In response, the photoemitter is designed to eject electrons having energies up to the kilo-electron volt level, with the number of electrons from any given area being a function of:

(1) the number of X-ray photons absorbed there, (2) the depth of absorption, and (3) the incident photon energy.

Upon ejection from the photoemitter, the electrons traverse the gap, being attracted toward the anode by the DC field. Any quenching gas resident in the gap decelerates the passing electrons, reducing their tendency to scatter upon impacting the receptor sheet and also increases the number of electrons through secondary ionization. The electrons, plus any negative ions which may be generated in the gap (by attachment to components of the quenching gas) are collected at the receptor as a "charge-image." The overall pattern of deposited electrostatic charge (latent electrostatic image), thus comprises an array of negative charges indicating the radio-transparency of (overlying portions of) the irradiated subject, with a relatively high charge density from areas which are more radio-transparent and less charge beneath areas which are more radio-opaque.

This latent charge image may then be made visible by development techniques well understood in the art, or at times by known cathode ray tube display techniques.

Described and illustrated herein are ionographic cassettes embodying the aforescribed anode/receptor sheet and cathode/photoemitter combination with intermediate working gap; the overall combination being here characterized as an ionographic record assembly or "cassette." The preferred embodiment of the subject invention will concern apparatus for manipulating, developing and otherwise handling such cassettes.

Problems — Objects

Following the discovery of the basic ionographic concepts a variety of methods and associated machines and devices have been proposed at various times to place Ionography on a more widespread, efficient, faster and

more commercial basis. For the most part, such devices have been quite limited in concept and intended only to handle narrow, specialized problems and, have lacked the versatility and widespread applicability necessary for putting ionography to use on a broad commercial basis. Although certain of these machines and devices are contemplated for relatively wide application, none can be considered to be really practical for a wide variety of ionography applications. For example, prior art machines (e.g. for similarly handling conventional film or Xeroradiograms) have been limited in the type and size of image records they can handle or in the manner and efficiency of record assembly and disassembly or in handling speeds (for both imaging and development). Associated with such limitations, of course, are related considerations of efficiency, speed, cost-control and reliability.

It is therefore an object of this invention to improve electrostatic record handling apparatus, and associated methods, so as to better implement and control the handling and manipulation of such records, especially for image development.

It is a further object to apply such apparatus to the development and fixing of images on ionographic media.

It is yet a further object to adapt such apparatus to "pre-packaged" ionographic cassettes.

It is yet a further object to adapt such apparatus for automatically transporting and otherwise manipulating such cassettes and automatically advancing them through treatment stations adapted to prepare, develop and fix the record media.

It is a further and related object to apply such apparatus for such manipulation including the preparatory opening and disassembly of such cassettes in a controlled automatic fashion.

It is yet another object to also provide for the automatic, controlled separation of receptor film from such cassettes, as well as for the storage of the remaining cassette portions for salvage, reuse, etc.

These and other objects of the invention will become more evident through consideration of the following disclosure and illustrative drawings wherein preferred embodiments are indicated, comprising in brief, an ionographic cassette development machine including entry means for accepting the cassette and performing unwrapping and image-record separating operations thereon; means for applying toner to the image record in a rapid, controlled automatic manner; means for fixing the so-developed image; and means for automatically advancing the image portions from one such treatment station to the next and ejecting it in a prescribed, efficient, controlled manner.

For a better understanding of the invention, as well as other objects and further features thereof, reference is invited to the following detailed description of the invention, especially its preferred embodiment, to be read in conjunction with the accompanying drawings, wherein like reference numerals refer to like parts comprising:

FIG. 1 is a top perspective view of an ionographic cassette assembly illustrative of record units adapted for handling by the apparatus to be described; and

FIG. 2 is schematic, fragmentary, sectional view of this cassette, with members enlarged and exploded apart for clarity;

FIG. 3 is a very schematic, upper perspective of such a cassette in position at each of the different stations of

the apparatus to be described; the illustrated condition of the cassette at each station and the schematic indication of various operating members being intended as a guide and overview to the successive cassette manipulations undertaken by the subject apparatus;

FIGS. 4 and 5 are upper-left and upper-right perspective views, respectively, of the preferred embodiment, of a cassette handling Film Processor to be described;

FIGS. 6, 7 and 7A are, respectively, a plan view, a front fragmentary elevation and an enlarged side-elevation, of the "cassette entry" station of the machine in FIGS. 4 and 5; with FIGS. 8 and 9 showing an enlarged fragmentary elevation and plan views, respectively, of the envelope-slitting elements of this station; while FIG. 9A indicates the cutter bar and knife elements of FIG. 9 exploded-apart for clarity;

FIG. 10 is a rather schematic functional showing of the transport elements of the foregoing machine shown in conjunction with cooperating driving and positioning members, together with illustrative ionogram record units being shown at successive treatment stations (after the manner of FIG. 3); these illustrative units being shown in plan view in FIG. 11;

FIGS. 12 and 13 are enlarged elevational side and end views respectively of one of the driving pawl elements of the transport assembly indicated in FIG. 10; while FIGS. 14 and 15 are elevational side and end views respectively of an envelope-slitting member of the same transport assembly; with FIG. 16 showing the pawl of FIG. 13 in conjunction with other portions of the chain loop and associated supporting and guiding members in operative relation with an illustrative ionogram record;

FIGS. 17 and 18 are plan and partly-sectional side elevation views respectively of the development station of the apparatus of FIGS. 4 and 5; with FIG. 19 indicating a somewhat simplified and differently sectioned end view of the elements in FIG. 18 and FIG. 19A showing an enlarged portion of FIG. 19; FIGS. 18, 19 also indicate illustrative cam actuation elements of this assembly as adapted to depress and raise the cassette during development as well as manipulate associated controls, these elements being indicated in perspective view and exploded away from one another for clarity;

FIG. 20, indicating in side-section, the toner powder delivery assembly operating in conjunction with the elements for this treatment station, these also being indicated in a somewhat simplified fragmentary schematic plan view, in FIG. 20-B, with a nozzle portion thereof indicated in enlarged front elevation in FIG. 20-A;

FIGS. 21 and 22 are plan and side elevational views, (FIG. 22 in partial section) of the fusing station portion of the apparatus indicated in FIGS. 4 and 5; with FIG. 21-A indicating the reflector of these figures in upper perspective;

FIG. 23 is a Timing Chart showing salient cassette treatment steps in conjunction with the operative state of some of the principal electrical and mechanical elements of the assembly; and

FIG. 24 is a schematic circuit diagram of the various electrical driving elements and associated switching and control elements for the machine of FIGS. 4 and 5.

Illustrative Cassette

As stated above, the invention has special advantages and utility when used in connection with a prescribed "prepackaged" arrangement of ionographic electrodes and associated elements, i.e. an "ionographic cas-

sette," although other rigid image record media may be similarly handled. A particular example is the cassette 111 illustrated in FIGS. 1 and 2, and for which the preferred handling apparatus embodiments later described are especially adapted, although workers in the art will understand that other cassettes may be used. Cassette 111 will be seen to comprise a multi-layered "sandwich" of electrodes, etc. enclosed in an outer, gas-tight envelope 113 having a connector assembly 115 through which the electrical (exposure) potential and the gap medium (gas; see terminals 115-a, -b) are to be supplied. Cassette 111 is more fully described in co-pending, commonly assigned U.S. Pat. Application Ser. No. 264,247, entitled "Cassette Unit," by Sidney E. Hindell filed on June 19, 1972 (herewith incorporated by reference).

Cassette envelope 113 preferably comprises a pliable, heat-shrinkable polymer film material, heat-sealed along one edge 117, being perforated to admit terminals 115-A, -B. Within envelope 113 are the basic ionographic imaging elements including an anode (receptor) assembly R and cathode (emitter) assembly E. Anode assembly R comprises a substrate plate 119 (preferably phenolic) providing a flat substrate on the lower face R-1 of which there is, a "hold-down" film 131 (discussed below) and (removably) affixed thereon, an image sheet, or receptor, 133 for receiving the charge-image. Although plate 119 may comprise a suitably flat, stiff radio opaque metal (e.g. Beryllium has been found suitable, properly treated for flatness), where, as here, it comprises a nonconductor, it must be provided with a suitable conductive anode surface (on R-1) — here provided by aluminum foil 121 or the like. A metal tab 123 is provided for electrical interconnection between anode surface 121 and other elements.

Disposed opposite anode surface 121 and receptor 133 thereon, and in spaced, parallel relationship therewith (see spacer 129), is the cathode assembly E comprising conductive cathode substrate 125 (e.g. aluminum), having a photoemissive layer (emitter) 127, preferably comprised of lead oxide. Emitter coating 127 is laid down as substrate 125 and adapted to emit electrons responsive to X-radiation incident thereon, as known in the art. The gap distance and the parallel relationship (between the receptor film 133 and emitter 127) are maintained by an intermediate spacer 129, formed to be coextensive with the peripheral margins of the two. Spacer 129 is nonconductive, with flat, parallel opposite faces 134, 135, and may be comprised of nylon or the like.

Receptor 133, as mentioned, is held (permanently) on anode 121, by a thin "hold-down" film 131 of a suitable adhesive material, preferably comprising a compliant vinyl material such as "Blue Vinyl" supplied by Tilley Manufacturing Co. of San Carlos, Calif. or other such known adhesive backing. Vinyl hold-down 131 is abutted very flat against conductive anode surface 121, completely covering it and adhering thereto. Then, the insulative receptor 133 may be affixed flat upon the adhesive face of hold-down 131 to become affixed removably thereto; to lie flat in parallel, equidistant relation with anode surface 121 and spaced equidistant from planar cathode plate 125 a prescribed gap distance. Film 133 is intended to be removed, manually, from hold-down 131 after the development of the latent electrostatic image (see below).

The charge image formed during the ionographic process must be deposited on receptor 133, which,

thus, preferably comprises a polymeric dielectric film (e.g. Mylar by du Pont).

Anode 125 has two gas ports 137 (only one shown) which communicate with respective openings 139 (only one shown), in photoemissive layer 127 adjacent the edge, thereof. Ports 137 admit gas into the gap area, between receptor 133 and emitter 127, communicating from outside through terminal tubes 115.

In assembling cassette 111, substrate 133 is first secured on flat anode surface 121 (of substrate 119) by holdown layer 131. Spacer 129 is bonded to the cathode 125 (actually to emitter 127 there) with a suitable adhesive and portion 141 of connector 115, which includes a front surface and a rear surface, is then attached to cathode plate 125. The connector fittings may be secured to one or both of the electrode surfaces for delivering electrical power thereto. The gas-tight envelope 113 may then be applied to enclose the cassette elements, functioning not only to seal out contaminants and seal in the gas but also to retain the entire assembly, maintaining the gap spacing between active electrode surfaces.

Workers in the art will appreciate that a cassette like the foregoing is advantageous for use in ionographic or related electro-photographic processes. Not only are the component elements unique and useful in themselves; but they are packaged and arranged for efficient, convenient assembly and disassembly (e.g. after the charge image on receptor 133 has been developed). For instance, cassette 111 provides a unit wherein the active (emitter, receptor) ionographic elements can be prealigned and assembled into a compact, readily-usable package, very conveniently; wherein the electrodes can be easily spaced from one another, and from the receptor film, using precise automatic equipment; wherein a quenching gas can be readily injected and maintained in the working gap; and wherein the receptor and its backing (rigid anode plate) can readily be manipulated (e.g. transported and positioned) with high speed, precise automatic equipment as specifically described below.

Cassette 111 thus facilitates production of ionographic images quickly and in rapid succession, since the cassette elements are preassembled and ready for use, requiring only a connection with a suitable power source/control unit. This cassette facilitates automatic disassembly (e.g. along cleavage-plane CP) whereby envelope 113 may be readily cut (preferably below plane CP — so plate R may slide laterally under, rather than over, the cut edge of the envelope, thus protecting film surface 33-S and leaving the latent (charge) image thereon undisturbed. Envelope 113 may be stripped away, along with the cathode-spacer assembly, leaving the receptor/backing anode unit (anode plate R) to be further manipulated automatically (e.g. for development and fixing), without requiring manual intervention and its associated costs, potential for error, etc. Thereafter, the receptor may be readily removed from the anode backing for further treatment and use. Such a cassette thus provides for the salvage and reuse of all elements save the shrink package 113 and the receptor film — but the latter may serve as its own print (positive or negative; e.g. transparencies). The invention, as detailed below, is directed toward providing equipment for automatically performing such manipulations on a cassette like this.

Processor Embodiment; Overview of Functions

Of course, this invention is principally concerned with manipulating discrete rigid electrostatic image media, such as ionographic cassettes, flat image film strips or sheets, or the like. Specifically, the principal embodiment herein concerns development apparatus for such media wherein individual record units, such as cassette 111, may be inserted into a machine for automatic disassembly, automatic advancement to successive development and fixing stations (and to related stations), to be, there, treated automatically, all under a prescribed program with precise machine control and requiring no operator intervention.

Referring now to the drawings, there is shown, in FIGS. 4 and 5, an "Ionographic Cassette Processor" 1 (development machine embodiment) for developing electrostatic (e.g. ionographic), image patterns from discrete ionographic cassette type media of the type aforescribed. Such media will be assumed to have been exposed in a prescribed manner to form the electrostatic image on its receptor; for instance, this being automatically effected using a prescribed mobile Exposure Console of the type described in copending, commonly assigned patent application Ser. No. 392,095, entitled "Ionographic Exposure Method Apparatus" filed Aug. 27, 1973.

The overall general machine organization and functions will now be described, referring also to FIG. 3 where a sample cassette is depicted as undergoing various salient manipulations by this machine. These are indicated here in a rather functional fashion (the particular implementing electrical and mechanical parts being shown and described elsewhere). Processor 1 has been intentionally designed, according to a feature of novelty, to both house the parts required in developing cassette film of the type described above, as well as to provide an attractive machine package which may be compatible for the typical user environment (e.g. office, clinic, hospital or laboratory) contemplated for generating and developing ionographic images and related operations.

The machine elements have been packaged in a relatively simple, compact, aesthetically-pleasing configuration with convenient modular dimensions (e.g. this embodiment being roughly 4 feet long by 3 feet high by slightly more than 1 foot deep). The machine includes a relatively flat top working surface with a removable hinged cover 2, conventional outer covering skins and access doors, plus a set of roller wheels 3 to make it movable. Supply and storage elements (e.g. Emitter bin 21, Receptor bin 71, air pump 85, Fuser Power Supply 81, Control Unit 83) are mounted for reasonably good access and servicing on a machine frame, based on a bed 5, most being accessible from the front, with few elements "hidden." Other, more "active" machine elements (e.g. inject drawer 31, Developer Chamber 50, Toner reservoir 51, fuser assembly 60 and associated elements, including Transport assembly 90 (— see FIG. 5 —) are suspended at the top of the machine for optimum operator access, monitoring, servicing of moving parts and "sensitive items" etc.

All equipment is adapted for conventional power sources (115 VAC, 60 Hertz; requiring a maximum of about 5 amps) with no plug-ins being necessary, such as for air, auxiliary power, pressurized gas, water, etc. As detailed below, the packaging is even arranged to store "discarded" cassette elements, i.e. those not serving as

the image record. In summary, the user need only roll this Processor into his lab, plug it into a conventional power line and switch-on the power interlock to "prepare" for use. Then, by his merely inserting a Cassette onto the inject-drawer, a full series of controlled development steps will be quickly (order of a minute) and automatically performed without his intervention and a finished ionogram delivered (eject slot 8) for his immediate use. Workers in the X-ray imaging arts will welcome such quick, easy, automatically controlled processing, and recognize what a step forward it constitutes over present day techniques with film or xeroradiograms.

Details of Processor 1 will be particularized later, but its general overall configuration will first be summed-up as follows: The treatment elements may be grouped into an Entry Station I, a Development Station II, a Fixing Station III and an Eject Station IV.

More particularly, the Entry Station I includes a cassette-holding drawer 31 into which cassettes of prescribed dimensions are inserted, being thereby pre-positioned in prescribed alignment with cutting and transport means, so that when drawer is pushed (fully) into the machine, automatic development of the cassette will begin, starting with automatic slitting of the envelope. The envelope is side-slit as the drawer is injected; then top-slit, so that a transport mechanism can automatically remove the receptor plate from its cassette assembly and advance it to the Development Station.

Development begins automatically when the plate reaches Development Station II, i.e. the plate is then lowered onto a powder cloud developer chamber where an aerosol cloud of toner dust is automatically injected and applied to the plate in a carefully controlled manner; this sequence being automatically terminated and the plate returned to the main advancement path when development (timed) is complete.

The plate is next advanced downstream to the fusing (fixing) Station III, where a fuser unit is energized to project a prescribed toner-fusing radiation fixing the powder on the receptor plate "on the fly."

Lastly, the plate is ejected at Ejection Station IV (slot 8) so as to be available for manual withdrawal. Here, the developed plate may, at the operator's pleasure, be manually removed and the image-film stripped from its anode backing plate to be used — this removal automatically "enabling" the machine for its next plate.

Workers in the art will readily appreciate that the foregoing arrangement and features of novelty for cassette handling are surprisingly well adapted for operator convenience and for efficient servicing and monitoring of sensitive parts, while yet employing means which are relatively simple, uncomplicated and reliable. For instance, the moving mechanical parts for advancing, cutting, developing and otherwise manipulating the cassette plates are very thoughtfully located at the very top of the machine (and unobstructed), at approximately "torso level," for convenient operator access, monitoring and intervention as necessary. In particular, the chain-driven plate transport is simple and compact in design and is located atop the other manipulative elements to be eminently handy for adjustments and servicing; yet it doesn't block observation of, or access to, the other means. The machine is also preferably provided with a lid 2 (shown only in FIG. 4) which is hinge-mounted and arranged to cover the top of the machine and isolate the inner elements (e.g. for safety,

muffling of noise and heat etc.). A convenient array of torso-level working surfaces are also thus provided, whether the lid is up or down.

Turning more particularly to FIG. 3, the aforescribed treatment station I through IV (injection, development, fixing and ejection, respectively) will, here, be rather functionally indicated in terms of the disposition and condition of a sample cassette plate as it progresses through each station. More particularly, at Entry Station I there is shown an illustrative cassette unit 111, to be understood as having already been inserted in proper alignment into the drawer 31 (when the drawer was retracted, fully, out of machine 1 — as in FIG. 5); with the drawer, then, being pushed fully into the machine, so as to thrust the cassette between a pair of opposed rotary knife assemblies EC, adapted to slit the sides of envelope 113 as aforesaid (such a slit being indicated by the dotted line SL — SL along the sides of cathode plate 125 in FIG. 2). These knives are more particularly described below (FIGS. 7-9) but may be generally understood, according to this "side-slitting" feature as engaging the (aluminum) cathode base plate 125 (see FIGS. 7, 8) just below the cassette "cleavage plane" (CP, FIG. 2) and wiping the envelope along the sides of plate 125 to thereby sever or otherwise rupture it just below plane CP, in both sides.

A second envelope-cutting action is next initiated, according to a "top-slitting" feature, being indicated, rather functionally, at station I as to be performed by a top-cutting blade TCB, here understood as having partially slit envelope 113 across its top midsection, transversely to the side-slits.

This "top-slitting" is quickly followed by a "plate-advance" sequence whereby a pushing pawl pp, is presented to engage the upper position of cassette 111 (i.e. receptor plate R) laterally, (Transverse to inject direction) from Station I toward Development Station II along appropriate guideways, this advancement being indicated in FIG. 3 as partly completed. Pawl pp is carried on, and driven by, a chain drive means (DCH here). Receptor imaging plate R will be understood as comprising anode base plate 123 together with imaging receptor film 133 and intermediate adhesive backing layer 131. This advancement will, of course, serve to separate receptor plate R from the rest of cassette 111 (at cleavage-plane CP) and push R to the right, see FIG. 7) with its "right edge" pushing out under the depending "side-flaps" of envelope 113, over spacer 129 to engage guideways T-g. Guideways T-g (see also FIG. 11) include an upward-canted leading-edge (left lip of base) so that plate R is immediately lifted up: away from the spacer 129, lest 129 interfere with the imaging surface (side-slitting above plane CP would allow these flaps to wipe image surface 33-S and might even damage the film 133).

Removal of plate R leaves the rest of the cassette assembly (emitter portion within the non-slit E in envelope 113) in place on drawer 31 at station I. When drawer 31 is next retracted again to the full-out position (FIG. 5), means are provided according to an "emitter storage" feature, to drop this assembly into storage. That is, stop means (edges 33-E on cutters EC) hold the "discard emitter" "IN," while drawer 31 slides out from under, and allow it to drop into emitter storage bin 21 (onto platform 34 thereof). As detailed later, this disposition of the lower cassette portion takes place somewhat later in the treatment cycle; however, it is suggested as an accomplished fact in FIG. 3 by its

disposition on lift platform 34 (note from above that emitter E comprises cathode plate 125, with attached photoemitter 127 and superposed spacer 129, together with connector unit 115, all being enclosed here in slit-envelope 113).

Receptor plate R is continually advanced until it reaches Development Station II, at which point the advancing mechanism is temporarily halted and according to a "toning elevator" feature plate R is then automatically lowered onto a "toning chamber" TC (or 51, FIG. 10) and later is raised again to resume advancement. That is, the "toning elevator" means is adapted according to this feature, to lower the plate into engagement with a powder cloud unit (functionally indicated in phantom as chamber TC) where the toner will be delivered uniformly to the image surface 133-S for development of the latent electrostatic image pattern there. After development, this means automatically raises the plate back up to resume engagement with its advancing pawl pp. According to a further, related "toner delivery" feature, this toner cloud is automatically generated, delivered and suppressed, synchronous with the indicated movement of the receptor plate, the composition of this cloud and its manner of delivery being carefully repeatably controlled.

Pawl pp now resumes its progress, advancing plate R toward the next downstream treatment station, Fixer Station III. According to another "flash-fixing" feature of this invention, the so-developed image on receptor plate R is "fixed" "on the fly" as it passes flash fixer unit FF. Unit FF includes lamps, the fixing energy of which is controlled to be so intense, yet so brief in energization (automatically synchronized with plate passage) as to require no interruption in plate advancement, given an appropriately large advantage in toner fusing speed over plate-advancement speed.

Lastly, imaging plate R is further advanced to a terminal position where it is presented through an ejector slot 8 at Eject Station IV. Here, according to a "single plate treatment" feature, the advancement mechanism is automatically stopped and left engaged with plate R partly emergent from the eject slot 8 to automatically bar initiation of the next plate-development cycle (of position switch) and also for withdrawal by the machine operator. Pawl P, etc. will thus prevent accidental "push-back" and re-engagement of the plate with any advance mechanism and consequent inconvenience and risk of damage. Withdrawal of the port-ejected plate automatically "enables" the next "development cycle."

According to the described embodiment, receptor film 133 is made manually removable from the adhesive "hold-down" layer 131 (on anode substrate 123), as indicated by the peeling-back of a corner of 133 in FIG. 3 at station IV. The operator thus may strip-off film 133 and store the anode substrate in bin 71. The foregoing treatment cycle will serve both to introduce and to summarize the salient functions of the machine embodiment, as a preliminary to the detailed description to follow. The foregoing should also provide a frame of reference for the following more particular description of machine elements, so they may be better understood in relation to the entire, integral machine organization. The Timing Chart of FIG. 23 also offers a summary, coordinated picture of machine functions and associated controls, and should be consulted in conjunction with the detailed description.

Processor Embodiment — Details

I — Entry Station (Cassette Opening)

FIGS. 6 and 7 indicate details of elements comprising the Entry, or injection, Station I discussed above together with associated cassette-opening and positioning means in more detail and enlarged; while FIGS. 8, 9 and 9A detail the envelope side-slitting mechanism, and FIG. 7A details the drawer latch.

In FIG. 6, drawer 31 is assumed to have been fully injected, manually (see handle 31-H), thus driving the cassette to the "fully-injected" condition; while FIG. 7 shows the beginning of the "plate-advance" sequence, with receptor plate R beginning its movement away from emitter E and Station I, along guideways T-g toward the Development Station II. In FIGS. 6, 8, cassette 111 will be understood as positioned on the drawer base 31, between side-positioners (i.e. left/right side brackets 31-RG, 31-RG' which engage drawer-rolls 31-R as well) and pushed by forward brackets 31-A, 31-A', to be, finally, stopped against end wall or stop, 31-EW. Drawer 31 is mounted relatively conventionally to be rolled on two sets of (forward/rear) roller pairs, one pair along each side of the drawer with each roll 31-R, projected, journaled on a respective axle from the machine frame. Each (left, right) pair of rolls is engaged by a respective double-flanged portion of drawer bracket 31-RG adjacent thereto, the flanges being fashioned to accommodate a roll pair as conventional raceway guides to thereby establish the insertion path for drawer 31. Full insertion of drawer 31 serves to impact the cassette against a latching "Drawer" switch, S-1 to lock it "in" (with Keeper 32-T, as indicated in FIG. 7A and described below) and initiate a number of Processor functions (e.g. transport start, fuse-charge).

As functionally indicated above, this "inject motion" drives the sides of the cassette past a pair of opposed slitting units EC which are arranged to cuttingly-wipe the adjacent passing side portions of envelope 113 against cathode plate 125 and so slit them. Slitting units EC are better seen in the fragmentary enlargements of FIGS. 8, 9, and 9-A. Units EC will be understood as each comprising a beveled disc blade 32 mounted on a hub 32-H adapted to be journaled for rotation in a receiving bore in a slitter bar 33 which in turn is relieved on one side thereof to accommodate most of the blade-disc while leaving a portion protruding. Bar 33 is mounted pivotably on the machine frame, being so disposed as to effect the described severing as a cassette is drawn past, being spring-urged inwardly beyond the locus of the cassette slides to present a prescribed cutting bias force (when urged backward away from the cassette as the latter begins to pass the disc blades) by suitable return springs 33-S and being so pivoted (about pivot 33-P) and stopped (pin 33-N) as urged by spring 33-S to normally assume a cassette-blocking position as indicated in FIG. 9. That is, once a cassette has passed beyond blades 32 into "fully-injected" condition (as shown in FIG. 6) (bar 33 edge 33-E thereof) will block cassette retraction. Blades 32 should provide the prescribed wiping action against the emitter plate 125 (aluminum preferably), yet without so badly abrading the plate, or themselves, as to be prematurely dulled and degraded. Use of such "wheel cutters" is well known in the art; of course, this operation may also be performed by other analogous means known to

workers. Slitting units EC are also adapted to dislodge the discarded cassette portions (emitter E plus envelope) from drawer 31, when the latter is retracted, to drop these into the emitter storage bin 21 (onto platform 34 thereof). More particularly, a flat 33-E across the inner end of bar 33 is disposed and adapted to engage emitter E being projected into the path thereof by the said spring-bias means. The cutter block 33 thus blocks return passage of the emitter/envelope assembly on drawer 31 once it has been injected therewith, and serves to hold them while the drawer is retracted so they may then drop onto the storage platform 34.

Side-rails or brackets 31-RG, 31-RG' thus serve not only as side bars defining the sides of drawer base 31, to align the cassette laterally, but also function as a raceway for the drawer rolls 31-R on their outer, channeled side. Right-hand rail 31-R' also serves as a stop retaining the lower cassette portion (emitter E) stationary when plate R is separated therefrom and advanced laterally by a push pawl P.

As seen in FIGS. 7-A and according to a "drawer latch" feature hereof, drawer 31 is provided with an "interference latch" or keeper arrangement adapted to prevent retraction of the drawer, once it is "fully-in" as in FIGS. 6 and 7-A, until a "release signal" is given. This prevents premature retraction of the drawer and insertion of a new cassette until a given treatment cycle is complete. This latch arrangement comprises a latch bar 32-T together with an associated bias spring 32-S and a releasing solenoid unit 32-M plus a return-spring 31-T, all mounted on the machine frame, together with a hook or detent 31-D mounted on drawer 31 so as to cock spring 31-T and be stopped by bar 32-T with the drawer "full-in" (FIG. 7-A). Thus, latch 32-T is pivotably mounted from the frame and spring biased normally "up" (i.e. the "on" or latching position) by spring 32-S. The top, inclined surface of 32-T wipes the lower surface of drawer hook 31-D (under its leading edge) as it is injected and lockingly engages the hook as shown (FIG. 7-A). As keeper 32-T is pushed off, it allows spring 32-S to lock the latch up under the hook. This bars retraction of drawer 31 until the latch is positively "upset" by being selectively reverse-pivoted downward to the "OFF" (down) condition by solenoid 32-M (clearing hook 31-D). The "release" electrical signal energizes solenoid 32-M to pivot 32-T down, clearing hook 31-D, and releasing spring 31-T so it will thrust the drawer outward; solenoid 32-M thereafter allowing 32-T to return up, ready to reengage hook 31-D on its next passage.

As aforementioned, the emitter storage bin elevator unit 340 (see FIGS. 6, 7) is so constructed as to present a storage bin 21 wherein a platform 34 is spring-suspended from a cable 34-S threaded over one or more pulley sheaves 34-P to be spring-urged (e.g. by conventional extension coil springs; not shown) into the uppermost position (as FIG. 7), when "empty;" i.e. absent the weight of discarded emitter plates E. This spring force is set so that the weight of the discarded emitters will depress the elevator in increments approximately equivalent to their height and so maximize compactness and storage capacity. That is, platform 34 is gravity-loaded by emitter plates. It will be automatically, gradually depressed against the action of the spring suspension means just sufficient to accommodate the next emitter E, continuing until it is "full." The spring force may be adjusted by providing variable mechanical advantage with selectable sheave combina-

tions with varying numbers of cable strands (adjustable mechanical advantage as known in the art). Storage platform 34 is mounted for vertical alignment through a rearward flange portion 34-G, thereof, provided to mount a pair of opposed guide-rollers 34-R journaled therein and engaged for rotation about respective opposed lateral guideways 34-RG so as to maintain platform 34 in prescribed vertical alignment as it moves up and down.

Transport Mechanism (Plate Advancement for Development, Fixing)

As functionally indicated above, a transport mechanism is provided to advance the Receptor plate R (or "film pack") from the Entry Station to downstream Developing and Fixing stations, while concurrently, according to another feature of novelty, providing cutter means adapted for, first, slitting the cassette envelope open across the top. Such a transport assembly 90 is (partly) shown in side elevation in FIG. 7 (the "entry end" thereof), while a very schematic, functional, simplified sideview is indicated in FIG. 10 which, together with the associated plan view in FIG. 11, indicates the operations to be performed by the transport mechanism in terms of plate manipulation (much in the manner of FIG. 3, above). Reference will also be had to FIGS. 5, 6 and 16, showing fragmentary enlarged detailed showings of the transport mechanism in upper perspective, plan and end views, respectively. Thus, transport assembly 90, best seen in FIG. 10 as an entirety, generally comprises a plate-advancing array or pusher pawls P, mounted on a chain/sprocket arrangement chain CH; (sprockets 90-SD, 90SI) for selective cyclical advancement along an elongate guide bar 91 defining the general path 90-CP of plate advancement. Guide 91 is supported by a plurality of brackets 92-A, 92-B attached to the top of the machine frame (FIG. 5). A pair of chain engaging spindles (driving spindle 90-SD and driven spindle 90-SI) are mounted and journaled at opposite ends of guide bar 91 and include sprocket wheels between which chain CH is threaded so as to be advanced thereby when drive spindle 90-SD is rotated (by transport motor 90-M, via timing belt 90-TB, as known in the art). Chain CH is adapted to carry a plurality (here, 3) of the plate-engaging pusher pawls (P-1, P-2, P-3) and an associated set of envelope-rupturing cutters (cutters C-1, C-2 and C-3), each cutter C being disposed on chain CH in prescribed spaced relation with an associated pawl (here, slightly more than a plate-width upstream thereof) and with one another. Both the pawls and the cutters are positioned, vertically and laterally (across the mid-section of the plate R, as transported) in precise, spaced relation with the plates handled thereby. Chain CH comprises a relatively conventional endless-loop, sprocket-driven chain familiar to those skilled in the art. As best indicated in FIG. 7, as chain CH is controllably (programmed for development specified) advanced by motor 90-M, being engaged by the sprockets, it will be slidingly advanced and guided along the upper portion of guide bar 91 (see FIG. 16) especially, according to a particular feature. That is, with chain CH engaged by a chain guide 91-G (specifically a grooved flange 91-GG thereof defining a raceway with bar 91) affixed on the bottom of bar 91, chain CH will be kept in prescribed alignment with the elongate axis of bar 91; this, in turn, will align with pawls and cutters along transport path 90-CP. This, according to another feature of novelty, provides a chain

supporting/directing means without the usual attendant difficulties of operation and maintenance, yet while maintaining the advancing chain in prescribed alignment with the plate transport path (its plane of advancement between successive treatment stations) and with associated guides and switches (see FIG. 11). This transport assembly is not only easy to manufacture and service, but may readily be made removable or adjustable in position. Obviously, chain CH may be conveniently threaded on the sprockets or disengaged therefrom, being located for easy access at the very top of machine 1. Support bar 91 preferably comprises an elongated metal bar of relatively-rectangular cross-section (e.g. preferably rigid, yet light, e.g. of hollow aluminum stock) with a smooth finish, at least on its upper surface for low frictional sliding engagement with chain CH there. Driving sprocket 90-SD is affixed to a spindle 909-SDA to be rotatably driven thereby, the spindle being journaled for rotation in bar 91 at one end, with its other end journaled at the side of the machine frame, where it, in turn, is drivenly-coupled with timing belt 90-TB (or any like belt and pulley arrangement). Idler chain sprocket 90-SI is, in turn, mounted on an idler spindle 90-SIA which is journaled for rotation between opposite portions of the machine frame and within intermediate bar 91, as well.

As best indicated in FIGS. 10 and 7, chain CH carries a prescribed number of pusher pawls P adapted for controllably advancing the latter between the treatment stations. Transport assembly 90 is disposed just above this plane of transport (see FIG. 10) to define the transport path 90-CP (taken by pawls P across the approximate center of the plate R). Pawls P may take any convenient form but preferably comprise the simple, bluntnosed linkage of FIGS. 12, 13 adapted to be mounted from the chain linkage (links CH-L) and adapted to present a flat, smooth plate-engaging surface P-S for engagement with plates R (trailing edge thereof) being disposed and dimensioned to engage most of the prescribed plate-height, but not projecting quite low enough to intersect the bottom plane of the plates lest it interfere with or damage the emitter E or other elements (e.g. of the machine) disposed just below plate R. Pushers P are depicted rather schematically, in FIG. 10 being arranged at prescribed locations about the length of chain CH and spaced so as to engage the trailing edge of successive film plates R. For example, in FIG. 10 pusher P-1 is shown just beginning to engage the trailing edge of plate PL-I (at entry or "plate-ready" position — see FIG. 11) and is spaced from its next preceding, downstream pusher P-3 along chain CH a sufficient distance so that as P-3 is just beginning to be disengaged from an associated ("completed") plate at position PL-IV (the end of the advancement path), cutter C-1 will be presented adjacent PL-I; ready to begin slitting the envelope of the next following cassette. Of course, this cutter C-1 is, in turn, separated by its associated (downstream) pusher P-1 so that P-1 will begin to engage the trailing edge of the next plate in order and begin advancing it along the transport path. Of course, this spacing of pushers and cutters will be adjusted to the overall dimensions of the advancement path of any given machine and to the selected dimensions of the plates used. For this embodiment (FIG. 10), it will be seen that a second pusher P-2 is also provided, being separated from the other two pushers by slightly more than the length of the advancement path

90-CP (here, defined as the distance between plate positions PL-I and PL-IV; FIG. 10 not to scale).

With the aforescribed operational transport mode, the pusher (pawls) must be designed accordingly. Thus, as best seen in FIGS. 12 and 13, a pusher P comprises a body portion P-B adapted to be attached (such as by welding, crimping or riveting) to an adjacent pair of chain links CH-L; and arranged to project an engaging extension P-T including engagement face P-S to engage plates R as mentioned. Extension P-T includes a bevelled corner P-L, provided to assure that the pusher clears plate R after disengagement with it (just beyond position PL-IV of plate — FIGS. 10, 11). Bevelled corner P-L is disposed to be sufficiently separated from the trailing edge of a plate at position PL-IV that during its upward arc about sprocket 90-SD it will "clear." Body P-B should be fastened between the adjacent portions of different chain links CH-L so that the pusher will be moved into, and out of, the advancement plane as "smartly" and as quickly as possible, executing a rather "square" corner, rather than a "curved arc" (the latter would be executed if bracket P-B were attached only to a single integral link (CH-L). For this embodiment, links CH-L are on a quarter-inch pitch.

As with pushers P, the top-slitting cutters C are arranged and disposed on chain CH so as to slit the upper surface of the cassette envelope promptly after it has come to rest at the Entry Station I (plate position PL-I), completing this slitting operation just before the plate is to be engaged by a following pusher. For instance, cutter C-1 is disposed along chain CH upstream of associated pusher P-1 by slightly more than a plate-width (about 11 inches here) to accomplish this. The other cutters, C-2, C-3, are likewise arranged and disposed on chain CH the same distance upstream of their counterpart pusher elements (P-2, P-3, respectively). As seen more completely in FIGS. 14 and 15, cutters C preferably take the form of a bi-part scissors probe for penetrating, then slitting, the envelope. Of course workers in the art will recognize that here, as with the pushers, other analogous forms may be used within the spirit of this overall invention.

Thus, cutter C in FIGS. 14 and 15 comprises a body portion C-B adapted to be fastened between successive chain links CH-L (preferably in the manner described above for the pushers P) and to present projecting, rupturing and severing portions comprising pointed probe C-L and opposed, inclined knife-edge C-C disposed in opposing, symmetrically-convergent relation with point C-R whereby to trap and sever envelope skin therewith. The rupturing, or penetrating point of C-R is mounted and arranged to be presented to the cassette envelope in a position to penetrate the envelope as the point of C-R is drawn around the curve defined by idler sprocket 90-SI, and begins its travel along the advancement plane (defined above), thus providing initial penetration of the envelope in an effective downward and forward thrust. This thrust is also adapted to rupture the side portion, between the top-slit and side-slits, as the envelope gathers and is pulled along. The tip C-R is constructed of relatively hard, thin metal stock (e.g. tool steel) for quick, effective penetration of the polymeric envelope, being about 30 mils thick by about 60 mils high (max.) and is projected forward of the severing juncture (of C-R with C-C) an appropriate distance, sufficient to stretch the envelope material somewhat for easy cutting, yet not so much as to effect a dragging build-up of envelope material upstream of the

cutting edge (in this case, a distance of $\frac{1}{4}$ inch is satisfactory). Cutting edge C-C is somewhat sharper, being comprised, when convenient, of a razor-blade; i.e. of spring steel and providing a rather sharply angulated edge on the order of $\frac{1}{8}$ inches long. A shank C-S is adapted to be tightly secured (e.g. with bolts) to the body C-B for retaining knife C-C in position there, removably (may be adjustable). A bevelled face C-F is provided on shank C-S for effecting a smooth gradual engagement-transition with the downstream envelope material, being adapted to engage it and thrust it downward, smoothly and gradually toward the cutting juncture. Unless this edge is so bevelled, the downward action might not be properly effected; indeed a sharp corner here would lead toward ragged and imperfect severing. Finally, cutters C are provided with a bevelled trailing edge portion C-T analogous to bevel P-L on pushers P, and provided for the same purposes of "clearance."

TRANSPORT OPERATION — SUMMARIZED

Turning now to FIG. 11, the mode of cassette advancement will now be described, somewhat functionally and briefly, in conjunction with an operational summary of how the advancing and positioning means and the associated (switch) controls interact, this latter being keyed to FIG. 23, a timing diagram indicating the comparative operational states of the significant dynamic mechanical (and electrical) elements of the processor embodiment 1. These operations are also indicated schematically in FIG. 10, and, to an extent, in FIG. 3.

A more complete description of the structure and function of the switches and other electrical controls and the operations associated with these may be had from consideration of the timing chart (FIG. 23) and the schematic machine control circuit in FIG. 24, and the descriptions thereof below. Thus, operation of switches and other electrical elements will only be summarized here, the structural and operational details thereof to be given later in describing FIGS. 23 and 24.

CASSETTE INJECTION

A cassette 111 is positioned on the surface of drawer 31, abutting stops 31-A, 31-A' and between opposed pairs of side rails 31-RG, 31-RG' (FIGS. 6, 7) adapted to receive cassettes of this size. The cassette is now at "Insert Position" PL-I' at Entry Station I (the "open" position of drawer 31, also indicated in FIG. 4). Drawer 31, carrying the cassette, is then thrust fully into machine 1 to carry the cassette into engagement with drawer stop 31-EW and, enroute, latching the drawer into the "plate ready" position, PL-I, (FIGS. 10, 11 and FIG. 7A; hook 31-D caught beyond latch 32-T, while cocking spring 31-T) and also wiping the envelope sides past cutters 32, thus slitting them. In the course of moving into position PL-I, the cassette will also trip "plate ready" microswitch S-1, which in turn will automatically indicate to the machine controls that: (1) the cassette has assumed position PL-I (2) the transport mechanism is to be started; and (3) the flash fuser is to begin charging its capacitor bank. Also, latch 32-T will now be "set" to hold back 31-D and the drawer and cassette at position PL-I until the drawer solenoid (see SOL-D, FIG. 24) is actuated to "release" and eject the drawer (e.g. when the plate treatment cycle is completed at position PL-IV; see below) — latch 32-T being pivoted down to release hook 31-D and spring

31-T released to push the drawer outward.

TOP SLITTING; PAWL ENGAGEMENT

With drawer insertion, and the cassette, now "side-slit" at the "begin transport" position PL-I and switch S-1 "closed," line power is applied to start Transport Drive 90-M (motor M-T, FIG. 24), which serves, through the indicated pulley linkage (FIG. 10) to start the rotation of drive sprocket 90-SD and, in turn, begin advancing chain CH thereon. This invokes the "top-slitting" phase wherein a cutter C is advanced by chain CH to pierce and then slit the envelope top as mentioned. Completion of this top slitting pass is followed by engagement of the associated downstream pusher pawl P with the film plate R to begin advancing R from position PL-I to the next position PL-II and toner application. This advancement, and all following Transport and Treatment operations of Machine 1 will be understood as automatically invoked and precisely-controlled upon initiation merely by drawer injection.

INITIAL ADVANCEMENT

Advancement of a plate R from position PL-I (FIGS. 10, 11) begins the initial phase of the transport cycle whereby the pusher pawl P begins to separate plate R from the rest of the cassette, sliding it out from under the envelope side-slit, onto a pair of opposed entry guideways TG, each comprising a U-shaped channel comprised of low friction material such as nylon, and adapted to maintain the lateral and vertical alignment of plate R as it slides therealong from Station I to Station II. Guideways TG (and similar downstream guides discussed later) thus serve to maintain plate R aligned vertically and laterally along a prescribed "advancement plane" 90-CP, established by the position of plate R atop its lower cassette portions positioned in drawer 31 (in "Full-In" position).

DEVELOPMENT STATION

Advancement continues along this advancement plane with the pawl P continuing to push plate R further beyond guideways TG at a prescribed rate (here about 18 ft/min) to next be engaged between a similar pair of opposed "developer-guides" 50-G constructed generally like guides TG; however, being mounted as described below to form part of a "Development Elevator" arrangement. Travel into and along guideways 50-G will continue until the leading edge of plate R trips micro-switch S-2, the "down initiate" switch tripped by the presence of the plate at Development Station II. Closing S-2 serves to interrupt the Transport and Exhaust operations, while initiating a development elevator. Elevator drive 50-M and associated mechanism is thus made to lower plate R, held between guides 50-G, onto the cloud chamber, where it may be "toned" by powder developing the charge-image. This Elevator later returns the (developed) plate upward for further advancement downstream to other treatment stations.

Toning is performed in precise automatic machine-controlled fashion (described below in more detail). The elevator mechanism is arranged to include a cam switch S-3 for monitoring elevator position, and initiating operations in accordance therewith. Thus, when the elevator "bottoms," engaging the cloud chamber, switch S-3 initiates the toning sequence (powder cloud generation; with a pump and pulse valve arrangement; plus attracting bias for grid and plate during a timed in-

terval — see below re FIG. 24); terminated by timing means, followed by a timed "settling sequence" (during which the toner cloud may settle, assisted by reactivation of the exhaust fan, and not escape outside the chamber when plate R is lifted away) and then automatic reactivation of the Elevator which begins returning plate R upward. When the Elevator has returned plate R up to the original transport plane to be re-engaged with its pusher pawl, cam switch S-3 will be shifted, causing the Elevator to be automatically shutdown and braked; and the transport drive to be reactivated and resume advancing plate R (toward the Fixing Station III).

FIXING STATION

The transport will now move plate R from Development Station II toward Fixing Station III, and will continue to advance R past Station III, flashing on-the-run, until reaching Eject Station IV. That is, when plate R begins to project beyond the confines of developer guideway 50-G, it will next be engaged guidingly by a similar fixer guideway 60-G similar to developer guideway 50-G and communicating therewith along advancement plane CP. This advancement will thrust the leading plate edge past a cooperating pair of micro-switches namely, "Complete" Switch S-5 and "Exit" Switch S-6, arranged in tandem along the advancement plane and adapted (as detailed below) to be "armed" and disarmed conjunctively by passage of plate R. That is, the leading edge of plate R will first trip S-5 then S-6, then switching them "ON" successively, thus causing drawer release, relay resetting and energizing indicators (allowing insertion of the next cassette). Next, the plate's leading edge will trip fuser switch S-4 to, then, flash-fuse the toned image "on the run" without any pause in the advancement sequence (sufficient to fuse the toner powder used) according to this feature of novelty. Thus, the position of S-4 is set to effect fusing at the proper point in the treatment sequence with the S-5/S-6 pair located somewhat upstream of S-4.

PLATE EXIT

Next, the trailing edge of plate R clears Switch S-5, initiating a "plate exiting" signal and automatically stopping and braking chain drive 90-M, thus leaving the plate at the final "eject" position PL-IV where its forward portions are projected through eject slit 8 for the machine operator to grasp and remove. According to another feature, the associated pusher, having reached the end of its advancement phase along path CP, is now stopped and braked adjacent the trailing edge of plate R, just prior to its upward movement around sprocket 90-SD, disengaging it from the plate. The pusher is held there until plate R is removed through slot 8 (this being registered by Exit Switch S-6). This feature is useful in preventing accidental re-entrance of a plate into the machine (e.g. by the operator's pushing it back through slot 8), avoiding any consequent inconvenience and possible machine damage. Thus, the "plate-exit" signal from S-6 (opened by plate removal) will enable S-1 so that, upon introduction of a following cassette on drawer 31 to trip S-1, S-1 is in condition to immediately initiate the next automatic transport/treatment cycle without fear that a prior plate is present downstream.

At this point, with machine 1 now beginning the next development cycle when chain drive 90-M begins to move chain CH, and a top-cutter begins its cutting ad-

vance, the pusher P at Exit Station IV that has been blocking reinsertion of plate R will be pulled up and around the idler sprocket and begin traveling back to Station I (to pick up another plate there — following the next two — there being three pushers in all here). As this pusher begins to move (beyond the extreme blocking position) a cutter begins this advance, approaching the "advance plane" 90-CP at Station I to begin slitting the envelope there. There will be provided a small "start-up" distance to get the cutter (chain) up to working speed (here about 1/4 inch is sufficient).

SUMMARY OF TRANSPORT MODE

The foregoing novel plate advancement sequence and mode of operation will impress workers in this art with its advantages and features; especially its susceptibility to simple, straightforward implementation, with readily available mechanisms. For instance, the embodiment uses relatively simple, available chain/sprocket drive; simple reliable pushing and cutting elements, very simple lateral guideways (for engaging and aligning the cassette as it is advanced) and known microswitch controls adapted to be actuated and invoke successive processing sequences by the mere passage and/or presence of the plate. Machine controls and operations are surprisingly easily invoked automatically by the imaging plate, providing self-monitoring and/or position-monitoring advantages, very important in this art.

While other equivalent advancing, manipulating and control means may obviously be employed to implement the described treatment cycle, workers in the art will appreciate how the described unique arrangement and design of these treating elements and their interrelation with the described type of transport means makes it possible to achieve a number of advantages. For instance, workers will appreciate the advantage of providing a transport path that is very straight and rectilinear and that lies along a flat plane; especially where this plane is disposed at waist-level atop the processing machinery. This obviously leads to marked advantages of simplicity and accessibility of the associated manipulation and control equipment, such as the chain and sprocket advance mechanism and associated lateral guideways. Such a design also optimizes monitoring of the position and condition of the plate during treatment by the operator, or by servicemen, or the like. That is, one can easily observe the plate as it is advanced through the treatment cycle and can spot and diagnose problems with a minimum of time or difficulty; without removing intermediate parts disabling the machine or even interrupting the treatment cycle. Another resultant advantage is that a "dynamic evaluation" and diagnosis can be given of machine operation; without interrupting machine operation in a treatment sequence, and simply by observation.

POWDER CLOUD DEVELOPMENT STATION II (TONER PARTICLE DELIVERY)

The structural details of the powder cloud development station II will now be described with reference to the preferred embodiment indicated in the figures, especially FIGS. 17, 18, and 19; although workers will understand that other equivalent means may in certain instances, be employed to effect the same operations and results. Thus, a box-like powder cloud development chamber 51 is provided having four walls, a top

(including a plate-receiving aperture 51-A), together with a removable pan or base 54, closing its bottom portion, plus various ports, and so adapted when engaged with a film plate to contain a powder cloud toning aerosol, as known in the art. As indicated, especially in FIGS. 18 and 19, plate-receiving aperture 51-A is cut into the upper surface of chamber 51 and is dimensioned and suitably gasketed to receive the subject plates sealingly thereon, as carried by the elevator guides 50-G, 50-G'. Thus, when a plate R is lowered down into operative adjacency with chamber 51 it is electrically contacted, and is sealingly engaged with the edge of aperture 51-A to form, with the plate and supporting guides, a relatively air-tight seal preventing the escape of toner dust during powder cloud generation. Escape of the toner cannot only degrade toning effectiveness, especially at the edges of the plate, but would soon tend to collect on and foul other portions of the machine. This contact and seal is preferably accommodated by the construction of elevator guides 50-G, 50-G' which are fashioned of nylon or other non-conductor including a plate-receiving groove defined above a lower lip portion 50-L, and exhibit an outer seating rim including a sponge rubber or similar seal strip 50-S thereon, adapted to engage the side edges of aperture 51-A and provide this guide-to-chamber seal as will be understood in the art. A like (flexible) lip and seal-seat 51-AL is preferably provided along the ends of hole 51-A. A set of flexible metal connectors 51-K are also provided along one or both sides of aperture 51-A and adapted for ohmic contact with plate R (conductive substrate side-tabs 123 thereof — FIG. 2) and connect Development bias potential thereto as understood in the art.

35 A toner-attracting grid 51-G is mounted in electrical isolation from chamber 51 and disposed a prescribed distance from the plate locus G-D (here about $\frac{3}{4}$ inches). As seen in FIGS. 18 and 19, grid 51-G comprises a set of base mounts G-M disposed on baffle 52 to support a cradle, including arms G-A and tension bracket G-T, therebetween, with a wire array G-W strung between arms G-A in electrical isolation therefrom, being connected through a power lead G-L to a suitable potential source (not shown). An electrical potential is applied to grid 51-G so as to attract the pre-charged toner particles toward the imagebearing surface of the film on plate R, thus serving to select toner of the desired charge polarity from below the grid wires, irrespective of the amount or disposition of (positive or negative) image-charge on the film substrate. As workers in the art will appreciate, such a development grid helps certain toning characteristics; for instance, pulling the entire cloud of properly charged particles close to the image-substrate, regardless of where the image charge is located or what its value is, and screening out a significant portion of any "wrongly-charged" toner particles (e.g. as often result with charging means of the type described).

The bottom of chamber 51 is closed by a pan 54 including an exhaust port leading to exhaust unit 55 comprising a selectively-operable blower and associated conduit means to pull down the toner aerosol (unit 55 is not shown in detail, but well understood and conventional in the art). Further, a filter screen 53 is disposed to overlie pan 54, being removable (for cleaning) and fabricated with filter apertures significantly smaller than the diameter of the toner particles contemplated and interposed to trap toner when the cloud is pulled to

exhaust by unit 55 preventing it from being thrown into the outer atmosphere adjacent the machine or its operating environment with obvious problematic results. Aperture 51-A with its compliant seating strips, 50-S, 51-AL (e.g. "Mylar") will be compliant enough to be pulled down and so provide an air inlet for exhaust unit 55. A baffle 52 is interposed across most of chamber 51 above filter 53, serving to catch and retain a significant portion of the toner particles which are not picked up by the film and settle thereon. Baffle 52 is constructed and disposed to leave a pair of side channels (or evacuation slots) 52-E, along two opposite sides being there, spaced from the sides of chamber 51 by a gap of about 1 inch. Slots 52E, 52E' are thus arranged to pneumatically couple the cloud chamber to the blower means of unit 55 (through filter 53) during exhaust phases and serve to entrain the exhaust flow along the sides of the chamber to thereby dissipate toner better, establishing better air-flow. Powder cloud chamber 51 and associated elements are mounted to be supported from the front and rear frame members MF-F, MF-R, respectively, of the machine frame, being attached to brackets extending therefrom (details not shown but of relatively conventional construction).

CLOUD GENERATION

The walls of chamber 51 also include a powder-inlet, or aperture, 51-F which the nozzle portion 127 of the powder cloud generation assembly 120 is fitted. The powder cloud assembly 120 and other associated structure and features are more completely described in co-pending commonly assigned application U.S. Ser. No. 269,880 entitled Improved Powder Cloud System filed on July 7, 1972. The general nature of assembly 120 may be generally indicated as including a (powder cloud) aerosol-generating supply vessel (aerosol reservoir) 124 in which the supply of toner particles is placed and into which a "whipping-tube air jet" is periodically injected at prescribed rate so as to generate an appropriate powder cloud aerosol (material suspended in air of appropriate toner density) under a prescribed over-pressure to be driven out to chamber 51. During a "toning interval" this will be continuously supplied to chamber 51 through an outlet 126, from reservoir 124, along a charging conduit 122-A (being charged during this passage) to nozzle 127 from which the cloud is to be projected into, and across, the cross section of chamber 51. Nozzle 127 is screwed into a fitting 127-F affixed to chamber 51 (see FIGS. 20, 20-A, 20-B). This cloud is to be shaped and directed for relatively homogeneous distribution by a prescribed nozzle slit configuration 127-S and by the disposition and configuration of fan-shaped diverter plate 122 extending over nozzle 127-S and into a portion of chamber 51, a prescribed distance. A pulsating air supply is arranged to be supplied from an air pump 127 (alternate gases and delivery means may be employed as contemplated by workers in the art) in conjunction with a selectively-opened valve 128 (via flexible pressure conduits 128-T) connecting pump 129 to a "free-end," resilient, delivery conduit, or "whipping tube," 125 in aerosol reservoir 124. Can 124 (e.g. aluminum about 3-1/4 inches by about 5 inches) is refillable, preferably including a lid 124-L, coupled through a suitable seal (e.g. O-ring 124-O) and suitably secured (e.g. by bolted clamp 124-C, being mounted from chamber 51 and bracket 124-B). As seen best in FIGS. 20, 20-A and 20-B, and as more completely described in the above referenced co-

pending application, U.S. Ser. No. 269,880, the air is supplied at a prescribed positive pressure by pump 129 and is periodically delivered, through valve 128 and inlet fitting 124-I, to tube 125 at a pressure and periodic pulsing manner which will, responsively, actuate tube 125 to be whipped, incrementally, around the top of the toner piled in reservoir 124 and so project a burst of air, while at the same time being reactively agitated (the end thereof is rotated and swept across the cross section of the cylinder 124 reciprocatingly) to thereby throw up a prescribed amount of toner into the atmosphere of reservoir 124, thus forming the contemplate aerosol cloud. Here, about 30 psi supplied in 60 millisecond bursts at about 50 pulses per minute was found quite suitable. As the powder cloud builds up in reservoir 124, the pulsating bursts of air will drive it out under prescribed pressure through outlet 126 and down the sinuous narrow passageway formed by conduit 122-A to exit into chamber 51, being spread there-across relatively homogeneously by nozzle 127 and deflector plate 122 (e.g. both stainless steel). Initially, of course, the reservoir can 124 will be filled almost completely with toner powder (i.e. the operator will make sure that it is almost full of toner particles, with a little air-space at the top); however, as the particles are used up by projection into the powder cloud and the pile level drops, it will be apparent to those skilled in the art that flexible tube 125 (e.g. 1/8 inch diameter silicone rubber) will still "whip up" the prescribed powder cloud nonetheless. That is, according to this feature, tube 125 is provided of sufficient length (exceeding the height of can 124 by a prescribed amount) that it will still provide its "whipping action" atop a toner pile closely adjacent the bottom of the can. Tube 125 will curve sinuously and re-entrantly (see 125') when the toner level is high, and be gradually extended and straightened more as the level drops.

According to another feature of this powder cloud generation assembly, charging conduit 122-A is fabricated of a type metal and includes such a sinuous shape and a suitably-narrow diameter and is so connected electrically as to charge the passing powder triboelectrically. That is, conduit 122-A comprises a narrow, constricted, rather tortuous passageway between container 124 and nozzle slit 127-S such that the toner particles will charge themselves triboelectrically by impacting one or many times against its metal walls in passing. Here, a stainless steel tube about 4 inches long, with a diameter of about 33 mils, and electrically grounded, was found quite satisfactory. The ground connection appeared to prevent any charge build-up in the tube itself, keeping its potential at a constant ground.

According to another feature, nozzle slit 127-S is made to comprise an extremely narrow, rectangular aperture communicating with tube 122-A through a small bore and associated intermediate chamber 127-C. Slit 127-S has an elongated major dimension, parallel to the plane of grid 51-G, and a transverse minor dimension, only a fraction of this major dimension (e.g. here a slit about 50 mils $\times$ 15 mils was found suitable where chamber 51 was about 10 inches $\times$ 14 inches by about 5 inches high). Deflector plate 122 is disposed just above slit 127-S and projected across a significant portion of the chamber cross section (e.g. here about 2 inches out from the side wall) and parallel to grid 51-G, being disposed enough above slit 127-S (about 1/4 inches here) to prevent excess projection of aerosol

against plate R. The horizontal disposition of the nozzle and deflector is important. For instance, it was found that aiming the nozzle up against a similar deflector gave relatively poor cloud generation and too much toner occluded to the deflector. With no deflector, the dispersion pattern was poor.

Maintenance on Processor 1, especially the Powder Cloud section, must be attended to; however, it is made relatively simple according to the described features. For instance, after a given number of toning cycles, the wires of grid 51-G should be scraped clean. This may be done automatically (e.g. after each cycle) by provision of a wiping shuttle on a reciprocator mechanism, or other means, adapted to sweep across the grid wires after toning, as desired. The toner supply in can 124 must be renewed periodically and the rest of chamber 51 wiped relatively free of occluded toner dust, with the nozzle and whipping tube being preferably solvent-wiped and the filter cleaned or replaced. Base 54 and baffle 52 will be periodically cleaned of toner piled thereon (i.e. unused toner not picked up by filter 53) — this and the toner from filter 53 may, in many cases, be desirable to reclaim. Further convenience may be achieved according to this design by simply replacing all the above elements, as an integral unit, with a factory-supplied (cleaned, etc) replacement unit.

Other maintenance will occur to those skilled in the art, but in any case will be surprisingly convenient. For instance, the cutting elements will be sharpened or replaced; drive motors, linkage (e.g. timing belts, chain, etc.) will be monitored for replacement and moving parts lubricated (or else made self-lubricating; e.g. as with the chain-guide). Workers in the art will also recognize that certain of the described toning elements may be otherwise implemented, consistent with the described concepts; for instance an alternative aerosol generation and/or delivery system may be provided; automatic grid-cleaning provided (e.g. as above mentioned) and parts modified (e.g. chamber 51 may be shortened eliminating the "dead space" beyond aperture 51-A, adjacent deflector 122 — see FIG. 18; perhaps accommodating storage of the mentioned grid-cleaning shuttle under each end of aperture 51-A).

ELEVATOR

Turning now to the development elevator mechanism 100, (see especially FIGS. 17, 18 and 19) it will be understood, generally speaking, that the film plate (as gripped between the opposed developer guideway channels 50-G) is to be lowered automatically from the transport plane (position PL-II) down to toning position PL-II; then back again. A pair of guide pins 50-P extend upward from each guideway 50-G to be accommodated in receiving bores in the associated U-shaped bracket, 114, each bracket, left and right (114-L, 114-R), thus accommodating a respective guide assembly and positioning it, being affixed to the machine frame. Pins 50-P carry an enlargement of seat 110-N about their mid section adapted to be drivingly engaged by a contacting end 121 of an associated (leading or trailing) rocker arm (112-L, 112-T, respectively). Arms 112 are adapted to be pivoted by prescribed rotation of elevator cam assemblies 110 mounted on either side of an elevator drive shaft 110-A and associated with a respective bracket 114-L, 114-R on either side of the advancement path in which the shaft is journaled. More specifically, as shaft 110-A is rotated, the rotation of an eccentric stub 110-S on each cam will serve to pivot an

associated pair of (leading and trailing) rocker arms (112-L, 112-T) to drive their outer, guide-engaging ends 121 downward and then return, to thus lower and raise the associated guide (50-G to 50-G') and plate R carried thereon. Elevator motor 50-M is drivingly coupled, through pulley linkage 50-C, etc. to shaft 110-A and thus adapted to rotate the cams in synchronism when energized.

Guides 50-G, 50-G' are, thus, driven down to present plate R for toning then back up again thereafter, in each transport cycle. More particularly, and as seen (for illustration) especially in FIGS. 18 and 19, guideway 50-G will be understood as presenting its pair of projecting pins 50-P (or plungers), each with an enlarged contact head 110-N thereon and with a suitable helical-coil return spring, SP wound around the pin, being captured between head 110-N and the lower flange on the bracket 114. The upper end of each pin is positioned slidingly in the upper bracket flange as noted. The enlarged head 110-N of each pin is adapted to engage the driving tip 121 of an associated rocker arm (or like cam linkage) and be driven down thereby (carrying the plate-holding guide 50-G therewith) during an "elevator-down" phase and be returned up, during an "elevator-up" phase (under the urging of return spring SP, when tip 121 is released by its cam). Each rocker arm 112 (i.e. "leading" arm 112-L with tip 121-LT plus "trailing" arm 112-T with its tip 121-TP) is drivably engaged with associated elevator cam mechanism 110 (see FIG. 17 including an eccentric cam stub 110-S projected therefrom eccentric with shaft 110-A and adapted to raise and lower tips 121-LT, 121-TP as the shaft is rotated as known in the art — or like cam linkage-means) and mounted rotatably about an associated pivot member (112-LP, 112-TP) so that as the stub 110-S is rotated eccentrically, it will pivot the outer arm tips 121 down in synchronism a prescribed distance to bring plate R into contact with the powder cloud chamber aperture 51-A as aforementioned. Opposing left and right elevator cam assemblies 110, mounted on shaft 110-a are of course rotated in synchronism when elevator motor 50-M drives the pulley linkage thereto (see FIG. 18 and timing belts 50-C, 50-C' mounted on pulleys to effect this coupling as known in the art; or like linkage).

Workers in the art will appreciate the advantages of this simple pulley/eccentric cam/rocker arm/plunger arrangement (or "cam-rocking-plunger") for reciprocating the plate-guide combination, and will understand that in certain cases other, equivalent means will serve.

As best seen in FIG. 17 and 18, cam shaft 110-A also mounts on a switching cam plate 103 for rotation and synchronous switch-actuation, as understood in the art, through engagement in cam-follower fashion with microswitch S-3 at selected points during the downward and return cycle of elevator assembly 100. More particularly, cam plate 103 is arranged to monitor the position of elevator stubs 110-S, 110-S' and includes prescribed radially-enlarged peripheral sectors on which the switch arm rides, switch S-3 being normally maintained in a first (or "up") state (see FIG. 24, described below) except during a passage of these enlarged sectors, when it will be thrust to a second (e.g. "down") state; returning thereafter (e.g. preferably under the urging of return-spring means). Thus, as switch S-3 is wiped along the outer edge of cam plate 103, it will remain "down" until the elevator stubs are rotated into

the "fully-up" position (corresponding to "fully down" for guides 50-G and plate R, now atop the cloud chamber) whereupon an enlarged sector portion of plate 103 will be presented to thrust S-3 to "down" (e.g. from line C-19 to line C-23 in FIG. 24), shutting-down elevator motor M-E. Other timing and switch means may then be provided to subsequently restart motor M-E, rotating the cam assembly yet further, with stubs 110-S rotating back "down" (the rocker arms pivoting up, urged by return springs (SP) to lift plate R back to the original transport plane, whereupon a reduced-radius sector of cam plate 103 allows S-3 to return to "up" state, shutting down the elevator again. In this manner, or an equivalent manner, workers in the art will understand that a cam/follower switch arrangement can be provided to monitor the elevated position of plate R and accordingly invoke responsive machine operations.

FIXING (TONER FUSED)

As indicated in the preceding summary, return of the image plate R, now toned, to the transport plane CP will (through the actuation of microswitch S-3) serve to automatically shut-down the elevator motor and to start-up the transport motor M-T resuming plate advance, towards fixing station PL-IV, where a flash fixing unit 60 will serve to heat-fuse the toner on the plate as it passes. Details of unit 60 are best understood with reference to FIGS. 21 and 22 wherein the flash lamp assembly is indicated in plan view and side elevation respectively, being shown in relation to the transport path and the associated machine parts; with FIG. 21-A showing the reflector box 61 in upper perspective. Flash fixer unit 60 comprises a pair of flash lamps L,L' housed in reflector box 61, including interior high-reflectivity surfaces along its sides and bottom except for a low-reflectivity portion 61-A between the lamps and on the ends. This optimizes usage of the toner-fusing radiation generated by the flash lamps as known in the art. A clear anodized finish on an aluminum surface (box 61) is preferred for providing this high-reflectivity, with a dull finish between the lamps (here, about 4 inches wide). This radiation is intended to be directed upwardly to bathe the image surface of the passing plate R with toner-fusing energy and is arranged such that the toner particles will be heated to melt and fuse against the surface of the image film on plate R, thus "fixing" the charge-image to render a relatively permanent image as known in the art. According to this feature, the flash lamps L,L' are selected to comprise Xenon lamps about as long as the image-surface (e.g. 10 inches) and are associated with a preselected capacitive power supply and control mechanism so that when triggered by switch S-4 they will provide a spectral radiation approximately equivalent to that of a 6000° K black body at the film plate. This radiation is so intense and so effectively picked up by the toner particles as to require only a very brief exposure; here on the order of 1 or 2 milli-seconds. This absorption of energy is so rapid, according to this feature, that it has been found that the film image may be flashed and adequately fixed "on the run," i.e. while being advanced at the aforesaid speeds (on the order of 18 feet per minute) and without stopping.

TYPICAL OPERATIONAL SEQUENCE — ELECTRICAL CONTROLS

Operation of the Processor, described above in various mechanical aspects, will now be summarized with

emphasis on electrical control aspects. Hence, the following describes a typical operational cycle, starting with initial preparation of the machine through complete development of an illustrative cassette 111, with concurrent to the Timing Diagram of FIG. 23 and the machine control circuit in FIG. 24. In FIG. 24, time will be understood as beginning with the closure of switch S-1 and the consequent initiation of transport drive 90-M and the development exhaust fan.

CONTROL CYCLE

Sequence (1) — Machine Preconditioning

In this typical operation, it will be assumed that Machine 1 has been properly preconditioned, being plugged into conventional line voltage (110 AC) with access doors and lid closed (interlocks on these closures are connected in series so that the opening of any one will shut down the entire machine), and with the proper control settings having been established.

For instance, a control panel located inside the Processor preferably includes three Development controls: a "development time control switch" to select a pre-scribed development time; a "target-thickness" switch to adjust (through a Variac) back-plate bias for differing target thickness, and an "image switch" to set for a positive or negative image, applying either a positive bias or ground potential to the film plate during toning. This panel will also house a fuse for the overall Processor and a fuse for the cassette counter. The development-time control can compensate for over-toning images having a unusually large percentage of dark areas by simply decreasing toning time, i.e. lighter toning for weaker charge-images. Longer development time should be set for images having relatively low contrast and low total "image charge," adjusting relay timer R-2. The target thickness switch adjusts toner-attracting development voltage; i.e. reducing it in cases of very weak image charge to avoid swamping out the image by applying too much toner across the entire plate.

A voltage adjustment for the lamps is also possible, i.e. for adjusting radiation intensity according to the fusing qualities of the toner used. Thus, lamp voltage may be increased for a toner that needs more radiation to melt and fuse it in a fixed discharge time.

Sequence (2) - Close S-1; Plate Advance:

With the machine thus preconditioned, a typical development sequence is begun by insertion of a cassette 111 into the cassette drawer 31 (see plate position PL-1', e.g. FIG. 11) in proper position by the operator and thrusting the drawer "home" to be latched into the second plate position PL-1 as indicated above. In the course of assuming position PL-1, microswitch S-1 is closed by impact of the leading edge of the cassette plate (emitter portion E; being held closed until E moves away). Thus, switch S-1 will remain closed until the drawer is "opened" (this being caused by energization of drawer solenoid SOL-D when S-5, then S-6 are closed — see below). Switch S-1 here comprises a "normally-open" microswitch adapted to indicate the presence of the adjacent cassette portion (as with the other microswitches herein) and may take any conventional presence-indicating format known to those skilled in the art. For illustrative purposes it will be assumed that when switch S-1 is closed, machine 1 has no other cassettes present in it (e.g. any prior developed

cassette will have been removed from eject slot 8).

Functionally speaking, closing switch S-1 will energize the exhaust and transport means (motors M-F, M-T, respectively, see FIG. 24); it will also initiate charging of the capacitor bank for the fuser lamps (indicated functionally in FIG. 24 as fuser supply FS). Note: here, as in all portions of the circuit in FIG. 24, the positions of switches and other elements shown will be assumed to be the starting, or normal, positions thereof.

Sequence (3) — Close S-2; Interrupt Advancement, Exhaust "OFF," Elevator "DOWN"

As indicated functionally in FIG. 11, the illustrative cassette plate will now be transported from position PL-I toward position PL-II until, upon reaching PL-II, the plate closes microswitch S-2 (normally-open, presence-indicating as with S-1). S-2, in turn, operates to "set" relay R-1 which, in turn, shuts down the transport drive and development exhaust means, pulling its switch arm R1-A from contact 10 to contact 11, thus disconnecting line voltage from the fan motor M-F and the transport motor M-T. Closure of switch arm R1-A starts elevator motor M-E, applying the line voltage thereto (whereby plate R is lowered by the elevator into operative engagement with the powder cloud development chamber for toner application as aforescribed: — power for motor M-E being applied along line C-15 through switch S-3, line C-19, relay contact R4-B and line C-7).

Sequence (4) — S-3 Rotated: Initiate Toner Cloud Generation; Duration Controlled by R2

As indicated functionally in the Timing Diagram, when the elevator mechanism completes its "Down" sequence, it synchronously shifts the operative position of switch S-3 "down," i.e. from connexion with line C-19 to connect with line C-23 at which point line voltage is applied to bias plate R for attracting toner (Back-plate bias — note: although separate grid bias can be applied, grid 51-G, is, here, tied to ground). This power is applied through relay arm R1-A, line C-15, switch S-3, line C-23, relay arm R4-A and associated machine elements to develop the back plate bias via the constant voltage transformer CV-X; Variac VAR and high voltage transformer HV-X.

Closure of switch S-3 also switches development timer R-2 "ON" so that for a prescribed, adjustable "Toning Time," an energizing potential is applied through timer arm R2-A to start air pump unit AP and associated pulsing unit PCU, these being shut-down after a prescribed "toning period," adjustably controlled by relay R2 (delay stage R2-d — which switches off line voltage after the delay for which it is set — see below). Thus, dropping of switch arm R2-A, after this set delay, shuts down toner units AP, PCU and also "starts" delay relay R-3 which controls settling time.

Pump AP develops a pressurized air supply for evolving a cloud of toner powder; while pulsing unit PCU synchronously interrupts the outflow from AP to generate prescribed air pulses. Thus, motor M-S is started with pump AP to periodically close an associated cam-switch S-7 connected to pulse a solenoid air valve SOL-P, and so provide prescribed bursts of air to generate a toner cloud for powder cloud chamber at a prescribed frequency. Pulsing unit PCU may also comprise known alternative mechanisms (e.g. cam-driven mechanical valving). This pulsing must be adapted to the configu-

ration of the various toning ducts and chambers used, the toner characteristics and the cloud-generating mode (— here, a whipping-tube mechanism —). For this embodiment, 60 millisecond air bursts (10-60 acceptable) at a rate of 50 per second (100 max) for about 30 seconds (according to the total toner desired) was found quite satisfactory. Timers R-2 and R-3 (and R-6, discussed below) preferably comprise time-delay relays of the "delay-on-actuate" type, adapted according to means known in the art to switch (move arm) only after a prescribed starting delay time; being "reset" by removal of line voltage (monostable arms return to original position). This delay time (toning period) is preferably made adjustable — here, by providing an R-C delay circuit with adjustable resistance ("potentiometer," with rectifier diode input — schematically shown as R2-d, R3-d, R6-d).

Sequence (5) — R-2 Switches, Toning Over: "Settling" Begins, Timed by R3

The switching of timer R-2 (arm R2-A) will in turn act to energize similar relay-timers R-3 and R-6. R-3 operates simply as a delay switch provided to introduce a prescribed "settling time" during which no toner is injected to chamber 51, the powder settling there prior to withdrawal of plate R. After this (adjustable) period, timer R-3 will switch, throwing arm R3-A to "set" relay R-4 and thus throw the associated switching arms (R4-A, -B and -C). This disconnects the R2 coil from line voltage, "resetting" it (arm R2-A returns up by itself).

The use of relay R-1 downstream of microswitch S-2 provides a "hold" or memory function in case of power interruption. For instance, if line power goes down shortly after S-2 is thrown, the system will "remember" that a plate has already reached the development position PL-II and that switch S-2 was tripped; whereas without such "hold means," with S-2 having opened, the controls for the elevator and various toning operations would be terminated and could not be resumed automatically — thus a given exposure image might be lost or damaged. Similarly, relays R3, R4 provide the system with a memory of powder cloud application and settling sequences having been completed. Relays R-1 and R-4 are mechanical latching relays tripped to a "set" condition by a prescribed set current pulse, remaining in this condition until "reset" by a prescribed reset current pulse (when S-6 closed) as known in the art.

As indicated, the "settling time" provided by timer R-3 may of course be made adjustable according to the effect desired by the operator. This may be effected in various ways known to those skilled in the art and acts to introduce a prescribed "dead-time" between toner cloud application (to plate R) and removal of the plate (toner "settles" in this time lest it escape when the plate is removed). Throwing arm R4-A also disconnects the development bias from plate R, as indicated in FIG. 24 and thus terminates toner-attraction. This will complete the development sequence, indicated in FIG. 23 as lasting typically about 40 seconds for this embodiment.

During an initial portion of this "settle-time," exhaust fan M-F is, after a brief delay, turned back "on" to help pull down the toner and settle it (through in other instances, this may be dispensed with), this "begin-exhaust" delay period established by the initial delay timer R-6, with switching arm R6-A being thrown

to connect line power to M-F after the delay, thus resuming cloud chamber exhaust to continue until S-5 is reset ("end of transport").

Sequence (6) — R4 Switches Elevator—Returns Plate "UP"

Closure of arm R3-A, applies a "set" pulse to relay R-4, throwing the switching arms thereof to: (1) start the elevator "up;" (2) remove Back Bias and (3) precondition the transport drive for later resumption of operation (when S-3 switches). More particularly, as seen in the circuit of FIG. 24, arm R4-B is thrown to re-energize elevator motor M-E for beginning the lifting of plate R back up to the primary transport path 90-CP (switch S-3 having been thrown down to contact C-23 when its cam-plate indicates "plate down," and thus applying line voltage to R4-B).

Also, throwing arm R4-C, preconditions transport motor M-T to be later energized (upon resetting of switch S-3 — S-3 in turn, being connected with line C-19 by further rotation of the elevator cam once the development elevator has lifted the plate fully-up to the transport plane). The throwing of arm R4-A disconnects timer R-2 from the line voltage (through S-3). Relay R-4 is later reset just prior to "fusing" when S-6 closes (R1 also reset then), resetting its switch arms (to the illustrated states). Sequence (7) — Cam Switch S-3 Stops Elevator, Starts Transport

Reverting back to primary functional diagram of FIG. 11, as well as FIG. 24, it will be seen that, with cam switch S-3 being rotated back "up," into contact with line C-19, and with relay arm R4-C now closed, elevator motor M-E will now be shut down and transport motor M-T now re-started by application of line-power thereto. Accordingly, advancement of the plate toward the Fixing Station (position PL-III) is now automatically resumed.

Sequence (8) — Close S-5; Bypass S-1

The further advancement of receptor plate R will thrust its leading edge past microswitch S-5, and shortly thereafter past microswitch S-6, closing these in succession. Shortly after this, further advancement will similarly cause plate R to close microswitch S-4 (these microswitches are of the presence-indicating type like switches S-1, S-2 aforescribed.)

Closure of S-5 serves to precondition S-5 for later detecting passage of the trailing edge of plate R, as well as switching the supply voltage circuit to bypass S-1 (when drawer 31 later opens), and so, nonetheless, maintain line voltage on Advance motor M-T and fan motor M-F, after switch S-6 has closed and S-1 is thereupon opened by release of drawer 31.

Sequence (9) — Close S-6 and R5; Open Drawer, Increment Counter; Reset R1, R4

Further advancement of plate R closes microswitch S-6, the Exit Switch, at the point where plate R is almost fully into the fixing station, and (with S-5 previously closed as well) acts: (1) to release the drawer, (2) to increment the counter, indicating that an image has been "processed," and (3) to illuminate READY lamp RL, and (4) to reset relays R1, R4.

More particularly, when S-6 closes, relay R-5 is energized to disconnect arm R5-A with switch S-1 and the line voltage (it was supplying to the fan and transport), while also connecting R5-B, in turn, to supply line voltage to activate drawer solenoid SOL-D, to increment

the counter CTR, bypass S-1 (via S-5 switching as above) and maintaining the line voltage to fan motor M-F and to drive motor M-T. When the drawer solenoid is pulsed, drawer 31 is unlatched and thrown-open, thereby carrying the Cassette emitter E away from switch S-1 and opening S-1. The transport drive, hereby kept "ON" via switch S-5, will later be stopped when S-5 is opened (by passage of the trailing edge of plate R, as indicated below).

Illumination of ready light, RL, and the opening of the drawer will now indicate to the operator that the drawer is ready for insertion of the next cassette to be developed in the machine; however as long as a prior cassette plate is present in exit slot 8 the operator must remove it before light RL will be extinguished (by opening of switch S-6) and before the processor may begin the next developmental cycle. That is, mere closing of drawer 31 with a new cassette in place, will not enable Processor 1 to begin the next "Development Cycle" — the prior (developed) plate R must first be withdrawn from exit slot 8 (and S-6 reopened) as before described. Thus, Relay R-5 stays on as long as S-6 is closed; when S-6 re-opens, R-5 drops out, disconnecting its arm R5-B and reconnecting arm R5-A for beginning a new machine cycle. Closure of S-6 also acts to apply a reset pulse, resetting mechanical latching relays R-1 and R-4, and thus restoring their switching arms to their initial condition, as indicated in FIG. 24 and described above in the beginning of the machine processing cycle.

Sequence (10) — Close S-4; Flash Fuse

As plate R is advanced slightly further to complete its journey into fixing station III, its leading edge will close microswitch S-4 to thereby fire the capacitor bank and energize the flash lamps for the prescribed period (—in this embodiment 1 or 2 milliseconds is used applying about 800 joules total, or about 10 joules per square inch on the image; different toner may require different radiation densities). This fixing and flashing is done "on the run," as described above.

Sequence (11) — Reopen S-5; Stop Transport, Stop Exhaust "End-of-Transport"

Further advancement of plate R will present its trailing edge past switch S-5, allowing S-5 to open, whereupon the line voltage being applied to transport motor M-T and to exhaust fan M-F will be disconnected, and these units shut-down at this point (M-T is then automatically braked vs "run-out" by plate R), thus effectively completing the transport cycle for plate R through machine 1. The position of Switch S-5 will accordingly establish this "end-of-transport" point with the subject plate projected through slot 8 a prescribed amount and engaged by its pusher pawl, at a point where the pawl is about to be pulled up out of transport path 90-CP, as described above.

Sequence (12) — Withdrawal of Finished Plate; S-6 Reopens; Machine Restored to "START" Condition

Of course, as mentioned above, plate R will remain in exit slot 8, kept engaged against its advancing pawl and thus barred from reinsertion into the machine, until the operator removes it, whereupon switch S-6 will reopen — whereupon ready light RL will be extinguished, and relay R-5 be released to resume its initial state (illustrated) as described above.

While the invention has been described with reference to a specific embodiment thereof, it will be understood by those skilled in the art that various changes in form and detail may be made without departing from the true spirit and scope of the invention. Accordingly, all substitutions, additions, and/or modifications of the present invention, or to which the present invention is readily susceptible without departing from the true spirit and scope of this disclosure, are considered part of the present invention.

What is claimed is:

1. Apparatus for automatically developing and fixing a latent electrostatic image carried on a rigid imaging plate having a high degree of flatness at least across an image-carrying portion thereof, said imaging plate constituting a portion of a cassette held in an assembled condition by a surrounding packaging envelope, comprising:
  - a transport path along which said imaging plate is unidirectionally moved;
  - an entry station including means for manually injecting an exposed ionographic cassette and moving it to the transport path, and envelope piercing and slitting means for automatically disassembling the cassette during said movement to separate the imaging plate therefrom whereby as the cassette is moved toward the transport path the envelope is progressively slit to free the assembled components of the cassette;
  - a development station including means for bringing the imaging plate into sealing engagement with a development chamber wherein the electrostatic image is contacted by a cloud of toner particles thereby to form a visible image on the plate;
  - a fixing station comprising means for fixing the image-defining toner particles on the plate;
  - an exit station including means for delivering the imaging plate carrying a developed and fixed image thereon; and
  - conveyor means for progressively advancing the imaging plate along the transport path from the entry station to the development station past the fixing station and to the exit station and for effecting a dwell period of predetermined duration of the imaging plate at the development station, all without adversely effecting the image-carrying portion or bending or distorting the flat imaging plate.

2. Apparatus as set forth in claim 1 wherein the disassembling means includes means for spatially separating the imaging plate from the balance of the cassette along an axis generally perpendicular to the plane of the imaging plate.

3. Apparatus as set forth in claim 2 wherein the entry station includes a drawer for deposit of the exposed cassette for subsequent sliding movement in a direction substantially lateral to and generally coplanar with that of said transport path.

4. Apparatus as set forth in claim 3 which further includes means responsive to the completion of sliding movement of the drawer for initiating action of the conveyor means whereby the separated imaging plate is

advanced at a substantially constant velocity to the development station.

5. Apparatus as set forth in claim 4 in which the entry station further includes means for receiving and temporarily storing remaining portions of each cassette after disassembly thereof.
6. Apparatus as set forth in claim 1 in which said entry station includes additional means for further slitting the envelope and separating it from the imaging plate.
7. Apparatus as set forth in claim 1 in which the envelope slitting means at the entry station includes lateral cutting means adapted to sever the envelope along the sides of the cassette.
8. Apparatus as set forth in claim 7 in which said cutting means includes stop means biased in a direction to permit movement of the cassette toward said transport path but prevent retractive movement relative thereto.
9. Apparatus as set forth in claim 1 wherein the transport means comprises an endless conveyor having one reach thereof extending the length of the transport path and carrying a plurality of spaced means for engaging and advancing an imaging plate along the transport path.
10. Apparatus as set forth in claim 1 which includes means responsive to the imaging plate arriving at the development station to effect relative movement of the imaging plate and the chamber in a direction perpendicular to the plane of the plate so that one surface of the imaging plate carrying the latent electrostatic image thereon is exposed to a cloud of toner particles within the chamber during a portion of the dwell period.
11. Apparatus as set forth in claim 10 wherein the means for effecting sealing engagement of the imaging plate with the chamber is an elevator which lowers the imaging plate from the transport path into engagement with the chamber and thereafter raises the imaging plate back to the plane of the transport path.
12. Apparatus as set forth in claim 11 wherein the development station includes means for clearing the chamber of the cloud of toner particles prior to raising the imaging plate from the chamber.
13. Apparatus as set forth in claim 1 wherein the fixing station includes means for fusing the image-defining toner particles on the imaging plate while it is moved along the transport path at substantially constant velocity.
14. Apparatus as set forth in claim 1 wherein the exit station includes an exit port at which the imaging plate bearing the developed and fixed image is presented for removal, and means responsive to such removal to enable the apparatus to be operated for a subsequent cycle of operation.
15. Apparatus as set forth in claim 1 wherein the cassette includes a photoemissive electrode portion in parallel spaced relationship to the imaging plate and the imaging plate includes a dielectric receptor sheet carrying the image, said receptor sheet being conveniently strippable from the balance of the imaging plate.
